UNITED STATES PATENT OFFICE.

JOSEPH E. HAUSFELD, OF CINCINNATI, OHIO, ASSIGNOR TO THE HUENEFELD COMPANY, OF CINCINNATI, OHIO.

HOT-BLAST STOVE.

1,121,557.

Specification of Letters Patent. Patented Dec. 15, 1914.

Application filed April 25, 1914. Serial No. 834,455.

To all whom it may concern:

Be it known that I, JOSEPH E. HAUSFELD, of Cincinnati, in the county of Hamilton and State of Ohio, have invented certain new and useful Improvements in Hot-Blast Stoves; and I do hereby declare the following to be a full, clear, and exact description of the invention, such as will enable others skilled in the art to which it appertains to make and use the same.

This invention relates to improvements in stoves and more particularly to hot blast rings for heating stoves,—the object of the invention being to provide simple and efficient means for effectually distributing the air blasts and to provide means located at the front of the stove for controlling the entrance of air to the blast ring.

With this and other objects in view, the invention consists in certain novel features of construction and combinations of parts as hereinafter set forth and pointed out in the claims.

In the accompanying drawings; Figure 1 is a front elevation of a portion of a stove embodying my improvements, with the door removed; Fig. 2 is a horizontal transverse sectional view; Fig. 3 is a vertical transverse section; Fig. 4 is a perspective view of a portion of the hot blast ring, and Fig. 5 is a horizontal transverse sectional view of a stove, showing the hot blast ring made to form a complete circle.

1 represents the body portion of a heating stove having a door opening 2 at its front.

A hot blast ring 3 is located within the body of the stove over the upper end of the fire pot and may be supported by a ring 3^a and by bolts 5^a passing through lugs 6 and through the stove body 1.

The hot blast ring 3 (which may be made in sections secured together) extends around the inside of the stove body from one side of the door opening to the other and, if lower than the door, said ring may form a complete circle, as shown in Fig. 5.

The hot blast ring is made with an upper sloping wall 4 and a lower convex wall 5, and the vertical wall of said ring may be formed by the body 1 of the stove, the latter thus forming one wall for each of two chambers or ducts 7—8 within the ring,—said chambers or ducts being formed by a horizontal partition 9.

55 The convex wall of the lower chamber or

duct 8 is formed with a plurality of openings 10, through which air may be discharged inwardly and downwardly into the interior of the stove,—this downward course bringing the heated air mixed with the rising gases in closer proximity to the burning fuel than would be possible were the discharge openings at or near the top or even on the inside circumference of the hot blast ring and therefore insuring ignition of the gases to a much greater extent than when allowed to rise high above the flames before being mixed with the hot air.

The lower duct or chamber 8 of the ring is closed against the ingress of cold air by a vertical wall 11, but means of communication between the upper duct or chamber 7 is provided by an opening 12 in the horizontal partition 9 about midway between the inlet ends of the ring, and a vertical partition 13 may be located in this opening, thus separating each of the two chambers 7—8 into two parts, whereby the air entering respective ends of the device may be separately controlled. The upper duct or chamber 7 is enlarged near each side of the door opening to form air inlet chambers 14, 14 communicating with said upper duct or chamber. Hoods 15 are secured to the outside of the body 1 of the stove and form parts of the inlet chambers, the wall of the stove body being made with suitable opening to permit free communication between the two parts of each of said inlet chambers. Damper plates 16 (which may, if desired form parts of the door frame) are secured to the hoods and are made with damper openings 17 to communicate with the inlet chambers. Dampers 18 are mounted on the plates 16 for controlling the inlet of air to the blast ring.

Air passing through either of the damper openings will enter inlet chamber 14 and from thence flow through the upper duct or chamber 7 to the opening in the horizontal partition, passing through this opening to the lower duct or chamber 8 and there, finding exit through the discharge openings 10 in the lower convex wall, will enter the combustion chamber of the stove at an angle inward and downward.

When a front section 19 (Fig. 5) is employed to form the blast ring into a complete circle, the said added section will be divided into upper and lower chambers with openings, in the wall of the lower chamber,

the same as in the other portions of the ring, and the upper chambers of said added section will be made to communicate with the inlet chambers 14.

5 With my improvements the hot blast may be regulated from the front of the stove and may be accurately controlled by regulating either or both of the dampers.

Having fully described my invention what 10 I claim as new and desire to secure by Letters-Patent, is:—

15 1. The combination with a stove having a door opening, of a hot blast ring having upper and lower chambers communicating with each other at the rear of the stove, and means at the sides of the door opening for directing air into the upper chamber of the ring, the wall of the lower chamber being inclined and having a plurality of openings 20 directing air blasts from said lower chamber downwardly and inwardly.

25 2. The combination with a stove having a door opening, of a hot blast ring having upper and lower chambers communicating with each other at the rear of the stove, the wall of the lower chamber being inclined and having a plurality of openings directing air blasts from said lower chamber downwardly and inwardly, enlargements at the ends of 30 said ring forming air inlet chambers communicating with the upper chamber, and means at the sides of the door opening for controlling the entrance of air into each of said air inlet chambers.

35 3. The combination with a stove having a door opening, of a hot blast ring terminat-

ing at respective sides of said door opening, said ring comprising end sections and an intermediate section communicating with each other and each having a lower inclined wall 40 provided with downwardly and inwardly discharging air openings, a vertical partition in said intermediate section, horizontal partitions in the end sections forming chambers segregated by said partitions from the 45 lower portions of said end sections having the discharge openings, said end sections provided with air inlet chambers communicating with said first-mentioned chambers, and dampers at respective sides of the door 50 opening of the stove for controlling the entrance of air to said chambers.

4. The combination with a stove having a door opening in its front, of a hot blast ring having a lower blast wall provided with 55 downwardly and inwardly discharging openings, partitions in said ring dividing the same into superimposed chambers segregated from each other at their front ends and communicating with each other at the 60 rear portion of the stove, and dampers at respective sides of the door opening for controlling the admission of air to the upper of the superimposed chambers.

In testimony whereof, I have signed this 65 specification in the presence of two subscribing witnesses.

JOSEPH E. HAUSFELD.
